UNITED STATES PATENT OFFICE

OLAF C. OLSEN, OF CLEVELAND, OHIO, ASSIGNOR OF TWO-THIRDS TO THE BORDEN COMPANY, OF WARREN, OHIO, A CORPORATION OF OHIO

REFRIGERATING APPARATUS

Application filed May 2, 1927. Serial No. 188,093.

This invention relates to improvements in valve control apparatus for refrigerating systems.

One of the primary objects of the invention is the provision of a control apparatus for a refrigeration system which will maintain the evaporating coil full of liquid at all times, and hence enable the system to operate with maximum efficiency.

Another object is to provide a casing through which the line from the compressor to the evaporating coil extends and including the expansion valve for that line, and through which the line from the evaporating coil back to the compressor extends, the two lines being maintained entirely separate from each other, but the conditions in the return line being employed to control the operation of the expansion valve which is in the other or outgoing line.

Another object is the provision of a stop, adjustable from the outside of the casing, for limiting the degree of opening of the expansion valve, it being possible also to manipulate the adjusting means so as to tightly close the expansion valve.

Still another object is the provision of means tending to provide an even circulation of lubricating oil.

Other objects, and objects relating to details of construction, will appear as I proceed with the description of that embodiment of the invention which, for the purposes of the present application, I have illustrated in the accompanying drawings, in which:

Fig. 1 is a diagrammatic illustration of a refrigerating system embodying my invention;

Fig. 2 is a transverse vertical sectional view of the control casing and its mechanism, taken on a line corresponding with line 2-2 of Fig. 1;

Fig. 3 is a longitudinal vertical sectional view of the same, taken substantially on line 3-3 of Fig. 2, to show a modified mounting for the valve stop;

Fig. 4 is a plan view of the casing with its cover removed.

Referring first to Fig. 1, the refrigerant

compressing and circulating pump is illustrated at 10, and the control casing at 11 with the cover therefor at 12. 13 is the condensing coil, and 14 is the evaporating coil forming the principal part of the refrigerating unit. The progress of the liquid and gaseous refrigerant through the system is indicated in Fig. 1 by the solid line and broken line arrows, respectively, while the conduit leading from the condensing coil to the control casing is marked 15, that from the control casing to the evaporating coil 16, that from the evaporating coil to the casing 17, and that from the casing back to the pump 18.

As will be observed, the connecting conduits all go to the casing 11 so that the cover 12 may be removed for the purpose of inspection without disturbing any of the connections, the stud bolts 19 being first removed. In order to make the casing fluid-tight, a gasket 20 is interposed between the casing proper and its cover 12. The threaded sockets for the reception of the nipples or connectors between the various pipes and the casing 11 are marked 15', 16', 17' and 18', and correspond with conduits 15, 16, 17 and 18 respectively.

The casing has two principal compartments, a float chamber 21 and an overflow chamber 22, separated by a dam 23. In the lower part of the overflow chamber is a cavity 24 which is formed partially by a recess in the bottom wall of the chamber and partly by a recess in the lower side of a horizontal partition wall 25, this cavity 24 being divided into upper and lower portions by a diaphragm 26 which extends horizontally across the cavity and is mounted between an interengaging annular shoulder 27 and rib 28 respectively, annular gaskets being placed both directly above and directly below the diaphragm so as to produce a tight joint. Clamping pressure to hold the partition 25 in place may be exerted by stud bolts 29 or the like.

Below the cavity 24 is a valve chamber 30 with a valve seat 31 adapted to receive a cone-shaped or needle valve 32 which has a head 33 fitted to slidably engage the side

walls of the valve chamber 30 and rounded at the top for engagement with the diaphragm 26. The valve seat 31 is located between the valve chamber 30 and a passage 34 which connects with the socket 15' through which fluid under heavy pressure enters the casing. There is another passage 35 leading out to the socket 16' from the chamber 30 and through which liquid refrigerant finds its exit at a lower pressure. The valve 33 is normally urged toward open position by a light coil spring 36. A passage 35' for communicating the pressure in passage 35 to the lower side of the diaphragm 26 serves to balance the pressure on either side of the head 33 of the valve.

At the center of the partition wall there is an upstanding projection 37 which extends well above the level of the draw-off 38 to the pump through socket 18' and conduit 18. The projection 37 is centrally bored to receive loosely a pin 39 resting at its lower extremity on the diaphragm 26 in line with the head 33 of the valve 32. The upper end of the pin 39 carries a head 40 flattened at its sides and provided with a transverse slotted opening 41 through which extends a pin 42. The head 40 is straddled by bifurcations 43 on a lever 44, these bifurcations carrying 43 the ends of the pin 42. The fulcrum for the lever 44 is provided by a pin 45 extending through the bifurcations 43 and mounted in ears or lugs 46 which extend upwardly from the projection 37. On the end of the long arm of the lever 44 there is a threaded extremity 47 for the reception of a threaded socket member 48 rigidly mounted upon a metal float 49 in the float chamber 21. To limit the height to which the float 49 may raise the pin 39 when the level of liquid in the float chamber is low and thereby to limit the degree of opening of the valve 32, I provide a stop 50 which takes the form of a vertically arranged pin with a flattened head 51. A coil spring 52 tends to raise the head 51. Over the top of the head 51 there extends the closed end of a metal bellows, the lower or open end of which is soldered to an annular disk or diaphragm 54 which is mounted at its periphery between a pair of annular gaskets 55 and 56 and clamped in place. This clamping effect is accomplished in the preferred form shown in Fig. 2 by a disk 57 threaded upwardly from below into a shouldered socket in the cover provided for that purpose, the disk 57 having a central hole to accommodate the pin 50. In this case the disk 57 also furnishes the abutment for the lower end of spring 52. In the modification illustrated in Fig. 3, there is an opening in the cover large enough to accommodate the pin 50 and the clamping of the annular diaphragm 54 is accomplished by a hollow nut 55 which is

threaded downwardly into a corresponding threaded socket in the cover wall.

In both cases, there is secured to the top of the bellows by any suitable means, as by soldering or welding, a reenforcing plate 56 with a slight depression in its upper face at the center which is engaged by a stud 67 threaded into an opening in the boss 58 in the case of Fig. 2, and in the hollow nut 55 in the case of Fig. 3. Movement of the pin 50 in one direction is thus accomplished by screwing in the stud 67, while its movement in the opposite direction is accomplished by the spring 52 whenever the stud 67 is backed off to permit the spring to act.

As previously stated, it is my aim to maintain the coil 14 full of liquid so that it may operate at maximum efficiency. Whenever the level of the liquid in the coil falls below the top thereof, gas alone will flow through conduit 17 to the control apparatus. Now there is a constant evaporation going on within the float chamber 21 as well as within the coil 14, in fact the chamber 21 is a part of the refrigerating unit. Consequently, when gas alone enters the chamber 21 and the liquid already there is evaporating, the level of the liquid begins to fall, the float 49 descends, raising the pin 42 and the pin 39 and permitting spring 36 to open the expansion valve 32, whereupon more liquid is forced from the condensing coil 13 through conduit 15, passage 34, expansion valve 31, 32, passage 35 and conduit 15 into the evaporating coil 14 so that the level of the liquid in the latter coil rises until finally liquid flows through conduit 17 into the float chamber, raising the level therein, whereupon the float rises and causes the pin 39 to be depressed and the valve 32 to be closed by means of the pressure of the pin 39 acting through the diaphragm 26 upon the head 33 of the valve, overcoming the action of spring 36. The valve will then remain closed until evaporation has proceeded again to an extent sufficient to lower the float 49, enabling the latter to raise the pin 39 and permit the spring 36 to again open the valve 32. In practice, the periods of valve opening and closing follow each other in rapid succession so that for all practical purposes the coil 14 is maintained full of liquid continuously.

As the valve 32 is an expansion valve, it is necessary to limit the degree to which the downward movement of the float 49 may cause the valve to be opened, and this is accomplished in my invention by a stop consisting of the pin 50, as previously explained. It is desirable to provide for the adjustment of this stop while the system is in operation, but ordinary methods of packing a longitudinally movable member are frequently not satisfactory in refrigerating systems because of the extreme difficulty in maintaining tight joints, particularly on the high pres-

sure side of the line in which the valve is located. I overcome these difficulties, first, by locating my adjusting means on the low pressure side, which I am enabled to do on account of the control working through a diaphragm 26, and secondly, by the provision of the metal bellows 53 which positively seals the opening in the casing required for the movement of the pin 50.

10 Lubricating oil which is mixed with the liquid entering the float chamber 21 from the pipe 17 collects on the surface of the liquid in that chamber and flows off over the dam 23 whenever the level of liquid rises 15 sufficiently to permit that action. The overflow chamber 22 becomes filled with lubricant up to the level of the bottom of the draw-off passage 38, and as additional lubricant is delivered to this chamber from the 20 chamber 21, it passes off, a small quantity at a time, through the pipe 18 back to the compressor.

Having thus described my invention, I claim:

25 1. In a refrigerating system, a casing comprising a float chamber and an overflow chamber, said float chamber being arranged to overflow into said overflow chamber, a take-off from the overflow chamber below 30 the level of the overflow from said float chamber, a valve chamber below said overflow chamber, a valve therein, a diaphragm mounted directly above said valve, said valve chamber comprising a cover for said diaphragm including a projection upstanding 35 above the level of said take-off, a valve operating rod mounted for sliding movement in said projection and engaging the diaphragm above the valve, a float in said 40 float chamber, and an operative connection between said float and said valve operating rod, whereby liquid collecting in said overflow chamber is prevented from flowing into the space between the diaphragm and its 45 cover.

2. In a refrigerating system, a casing, a passage through the bottom of said casing adapted to be connected in series between the condensing coil and evaporating coil of 50 the system, a valve in the casing arranged to control said passage, said casing having a cavity above said valve, a diaphragm dividing said cavity into two compartments, a take-off for fluid in said casing above said 55 cavity, means for operating said valve through the intermediacy of said diaphragm, said casing having an internal portion upstanding above the level of said take-off through which portion said means extends.

60 3. In a refrigerating apparatus, the combination of a circulating system including an evaporating coil and a condensing coil, a casing having a float chamber and an overflow chamber, a dam between said two chambers, a connection to said float chamber from

said evaporating coil, a take-off from said overflow chamber located below the level of said dam, a valve chamber in said casing, a passage in the casing connecting said condensing coil and evaporating coil, a valve in 70 said valve chamber arranged to control said passage, a float in said float chamber, operating connections for said valve actuated by said float extending through said overflow chamber, a diaphragm separating said valve from said operating connections, and means for preventing liquid in said overflow chamber from contacting with said diaphragm.

4. In a refrigerating apparatus, the combination of a circulating system including an evaporating coil and a condensing coil, a casing having a float chamber and an overflow chamber, a dam between said two chambers, a connection to said float chamber from said evaporating coil, a take-off from said 80 evaporating coil located below the level of said dam, a valve chamber in said casing below the level of said take-off, a continuation of said valve chamber extending above the level of said take-off, a passage in said casing connecting said condensing coil and said evaporating coil, a valve in said valve chamber arranged to control said passage, a float in said float chamber, operating 85 connections for said valve actuated by said float and extending through said continuation of said valve chamber, and a diaphragm between said valve chamber and said continuation separating said valve from said operating connections.

In testimony whereof, I hereunto affix my signature.

OLAF C. OLSEN.
